US0D1067968S

(12) **United States Design Patent** (10) **Patent No.:** **US D1,067,968 S**
(45) **Date of Patent:** **** Mar. 25, 2025**

(54) **POINT-OF-SALE TERMINAL**

(71) Applicant: **FUJIAN NEWLAND PAYMENT TECHNOLOGY CO., LTD.**, Fuzhou (CN)

(72) Inventors: **Jujie Zhang**, Fuzhou (CN); **Cuiting Zhong**, Fuzhou (CN); **Xuanqing Chen**, Fuzhou (CN); **Xiaoan Wang**, Fuzhou (CN)

(73) Assignee: **FUJIAN NEWLAND PAYMENT TECHNOLOGY CO., LTD.**, Fuzhou (CN)

(**) Term: **15 Years**

(21) Appl. No.: **29/909,943**

(22) Filed: **Aug. 14, 2023**

(30) **Foreign Application Priority Data**

Feb. 17, 2023 (CN) 202330056570.2

(51) **LOC (15) Cl.** **18-01**

(52) **U.S. Cl.**

USPC **D18/4.4**; D18/4.6

(57) **CLAIM**

The ornamental design for a point-of-sale terminal as shown and described.

DESCRIPTION

FIG. 1 is a perspective view of a point-of-sale terminal showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the point-of-sale terminal where the point-of-sale terminal is in a configuration of use. The broken lines in the drawings depict portions of the point-of-sale terminal that form no part of the claimed design.

1 Claim, 9 Drawing Sheets
